HAIR GUIDING ATTACHMENT FOR HAIR CLIPPERS

Frank Fewins, Los Angeles, Calif., assignor of one-fourth to Daniel J. W. Huntington, Los Angeles, Calif.

Application November 13, 1947, Serial No. 785,594

3 Claims. (Cl. 30—200)

1

This invention relates to an attachment for the conventional hair clippers of the type embodying a pair of relatively reciprocable abutting toothed blades, for the purpose of guiding the end portions of long hair between the teeth of the cutter blades.

An object of the invention is to provide a hair guiding attachment for hair clippers whereby the latter may be readily adapted for use in trimming long hair; it ordinarily being difficult to manipulate hair clippers in hair trimming operations because the cutting edges of the clipper teeth extend to the tips thereof so that a cutting action is affected immediately on engagement of the hair by the clippers.

A particular object of the invention is to provide a hair guiding toothed extension to the leading edge of the conventional hair clippers which will function to separate and break up clumps of hair in a fashion to effect a distribution of the hair between the tips of the cutting teeth of the clipper as the latter is advanced relative to the hair and also to provide a construction in the attachment whereby it may be readily applied to and easily removed from the fixed lower clipper blade and be securely held in place thereon solely by a clamping or gripping action thereby obviating the use of supplemental pins or screws or the like, and also obviating any alterations or changes in the clipper construction in order to adapt it for application of the attachment.

A further object is to provide an attachment of the above character which may be slipped in and out of engagement with a clipper blade and when applied be held in wedge engagement with the ends of the blade together with snap engagement with the rear margin of the blade in such manner as to securely retain the attachment in place and hold it in a positive fashion against accidental movement relative to the clipper blade so as to maintain the hair guiding teeth of the attachment in proper alignment with the cutting teeth of the clipper.

A further object is to provide an improvement in hair guiding attachments for hair clippers which may readily be formed in one piece of sheet material.

With the foregoing objects in view, together with such other objects and advantages as may subsequently appear, the invention resides in the

5 parts and in the combination, construction and arrangement of parts hereinafter described and claimed, and illustrated by way of example in the accompanying drawing, in which:

Fig. 1 is a perspective view of the attachment,

Fig. 2 is a plan view,

Fig. 3 is a rear elevational view,

Fig. 4 is a side view,

Fig. 5 is a view in side elevation of the cutting head of a pair of clippers showing the attachment as applied,

Fig. 6 is a view in transverse section of the lower fixed cutting blade of a hair clipper showing the attachment as applied, and illustrating in 15 dotted lines the manner of effecting removal of the attachment, and

Fig. 7 is a perspective view of a fragmentary portion of the hair guiding attachment showing the teeth thereof spaced apart in a skip-tooth 20 arrangement.

Referring to the drawings more specifically A indicates generally the cutting head of a conventional hair clipper which embodies a fixed blade B and relatively slidably blade C reciprocally mounted and slidably supported on the upper face of the fixed blade. The forward edges of the clipper blades B and C are formed with hair cutting teeth D and E. The lower faces of the teeth D are inclined upwardly from the flat underside F of the blade B to the outer ends of the teeth. The blade B is characterized by having a longitudinal transversely inclined edge a on the underside of its rear portion.

The present invention resides in a hair guiding attachment for the lower toothed blade B which embodies a plate portion 7 adapted to overlie the underside of the flat face F of the blade B from the forward edge of which plate extends an upwardly inclined toothed plate portion 8 arranged to underlie the inclined undersides of teeth D and to conform thereto in close contact therewith; the plate portion 8 being formed with a series of hair guiding or feeding teeth 9 which protrude a short distance beyond 35 the tips of the teeth D and E of the clipper. The teeth 9 may be spaced any suitable distances apart, being generally spaced in accordance with the spacing of the teeth of the hair clippers, but not necessarily so since there are occasions where it is desirable that the spacing of the teeth may

be either more or less than that of the clipper teeth.

Formed on each end of the toothed plate 8 are outwardly projecting flanges 10 and 11 which are tapered longitudinally to conform to the taper of the teeth D at the ends of the clipper blade B which flanges are provided with inturned lips 12 and 13 respectively on the upper margins thereof. The lips 12 and 13 are adapted to protrude over the upper face of the end teeth D in abutting relation thereto so as to coact with the inclined plate 8 in affecting wedge engagement between the attachment and the end teeth of the blade B.

An important feature of this invention resides in forming the plate 7 on the margin thereof opposite the juncture with the toothed plate 8 with a resilient tongue having its outer end adapted to be engaged with the rear edge *a* of the clipper blade B. As here shown a pair of such tongues 14 and 15 are provided which are spaced apart and terminate in upstanding outwardly inclined flanges 16 and 17, terminating in outwardly projecting flanges 18 and 19; the inclined walls of flanges 16 and 17 being adapted to engage the edge *a* of the blade B as particularly shown in Fig. 5.

The flanges 10 and 11 with their associated in-turned lips 12 and 13 form open ended opposed tapered channels 20 and 21 the large ends of which are presented toward the plate 7. In applying the attachment the side margins of the teeth D of the plate B are positioned in engagement with the flanges 10 and 11 and lips 12 and 13 by inserting the end teeth D in the large ends of the tapered channels 20 and 21 and advancing the attachment and blade B relative to each other until the upper and lower margins of the teeth are snugly seated between the lips 12 and 13 and the plate 8. When this occurs the inclined flanges 16 and 17 will snap into engagement with the edge *a* of the blade B as shown in Fig. 5. The attachment will then be securely held in place on the blade B.

When it is desired to remove the attachment the gripping flanges 16 and 17 and the tongues 14 and 15 are moved downwardly as indicated by the dotted lines *b* in Fig. 6 to dispose the grips out of engagement with the edge *a* whereupon the side grips formed by the flanges 10 and 11 may be slipped outwardly and withdrawn from engagement with the end teeth of the clipper. In order to facilitate disengagement of the flanges 16 and 17 from the edge *a* the portion of the inclined plate portion 8 adjacent its intersection with the plate portion 7 is formed to project downwardly from the inner ends of the lower inclined faces of the clipper teeth D when the end teeth D are snugly seated in the tapered channels 20 and 21 so that the plate portion 7 and the tongues 14 and 15 will extend in slightly spaced relation to the underside of the blade B and thus be out of contact therewith and also space the rear edge of the plate portion 7 from the blade B. By this arrangement the marginal portion *c* of the plate 7 and the contiguous portions of the tongues 14 and 15 are projected so as to be readily engaged by the tip of the thumb or a finger and a forward thrust imposed on the attachment so as to cause the inclined flanges 17 to ride over the inclined edge *a* and thus free the tongues 14 and 15. The clearance afforded between the plate portion 7 and the underside of the clipper blade B facili-

tates withdrawal of the end teeth D from the channels 20 and also facilitates insertion of the end teeth in the channels in applying the attachment.

5 In the operation of the invention when the attachment is applied to the clipper the protruding ends of the teeth 9 will on being advanced into the hair to be clipped act to separate the hair and effect feeding of separated groups of hair 10 to the cutting teeth of the clipper, thus enabling the operator of the clipper to trim the ends of the hair in a fashion ordinarily accomplished by the use of comb and shears in barbering operations.

15 In the construction shown in Figure 1, the teeth 9 of the hair guiding attachment are shown as of a width and spaced apart such as to correspond to the teeth and spaces therebetween of the clipper blade to which the attachment is to be applied. Fig. 7 illustrates another construction in the attachment in which a wide spacing is afforded between adjacent teeth in what is known as a skip-tooth arrangement where every other tooth of the ordinary construction shown in Fig. 25 1 is eliminated. This arrangement is found advantageous where it is desirable to feed the hair to the clippers in greater quantity and faster than can be effected by closer spacing of the teeth.

While I have shown and described a specific 30 embodiment of my invention I do not limit myself to the exact details of construction set forth, and the invention embraces such changes, modifications and equivalents of the parts and their formation and arrangement as come within the 35 purview of the appended claims.

I claim:

1. A hair guiding attachment for hair clippers comprising a toothed plate, an upstanding longitudinally tapered flange on each end of said 40 plate, an inturned lip on the upper margin of each of said flanges, and at least one spring tongue carried by and extending rearwardly on said toothed plate having an upstanding flange thereon.

45 2. A hair guiding attachment for hair clippers having a fixed blade formed with cutting teeth including end teeth, a toothed plate, open ended longitudinally tapered channeled members on the ends of said toothed plate adapted to receive the end teeth of the clipper blade in wedge engagement therewith and means on said toothed plate for releasably gripping the rear portion of the clipper blade.

55 3. A hair guiding attachment for hair clippers having a fixed blade formed with cutting teeth including end teeth, a toothed plate, open ended longitudinally tapered channeled members on the ends of said toothed plate adapted to receive the 60 end teeth of the clipper blade in wedge engagement therewith, a rearwardly extending spring tongue on said toothed plate, and a blade gripping flange on said tongue.
